UNITED STATES PATENT OFFICE.

EDWARD MUEHLBAECHER, OF LOS ANGELES, CALIFORNIA.

PROCESS FOR FINISHING ART GOODS.

No Drawing.

Application filed May 31, 1921. Serial No. 473,958.

To all whom it may concern:

Be it known that I, EDWARD MUEHLBAECHER, a citizen of the United States, and a resident of Los Angeles, in the county of Los Angeles and State of California, have invented new and useful Improvements in Processes for Finishing Art Goods, of which the following is a specification.

This invention relates to an improved process for producing artistic finishes on art objects, furniture, mantels, fixtures, walls and the like.

The invention has for its main object to provide an economical process for providing an artistic finish on art objects and surfaces of the above character that may be readily applied by practically unskilled persons.

It will be understood in the consideration of the invention that a great demand exists for reproductions of art objects produced by skilled artisans in prior generations, particularly those produced during certain "periods" or epochs of the history of art. The originals were constructed of iron, stone or wood and after years of use and exposure to the elements have acquired a characteristic appearance such that cannot be ordinarily reproduced except by skilled artisans. Where iron was the material employed the surface has become oxidized and pitted and therefore to faithfully reproduce the object great skill is required and the cost of reproduction including time, material and labor becomes excessive. Where the material used was stone or a moulded plastic material the surface thereof has taken on a roughened appearance and a characteristic color. It is therefore another object of my invention to provide an improved process or method for economically reproducing an age worn surface characteristic of iron or stone; which process may be carried out by employing common and inexpensive materials in the hands of unskilled persons without the use of other than readily handled tools or appliances.

It will also be understood that certain colors and combinations of colors such as were used extensively by peoples of previous times, as the Egyptians and Greeks, are in vogue because of their appeal to the eye and because of their absence of conflicting or inharmonious tones or vibrations, the psychological effects of which have long been recognized. I refer to so called live

colors, it being understood that coloring compounds or paints in which oils or similar vehicles are used are not particularly applicable to large areas of walls, ceilings and the like, inasmuch as the live qualities of the coloring pigments are altered by the presence of oil.

It is therefore another object of my invention to provide a process for finishing walls, ceilings and like areas in which the colors are not altered by the presence of oils and by which process the surface is given a roughened or pitted surface as in the case of imitation of antique iron or stone objects which proved to be particularly pleasing and artistic and does not have the appearance of mere painted plaster walls.

A further object of my invention is to provide a process applicable alike to practically all varieties of art objects and surfaces so that persons unskilled in such arts may use the process without involving great expense while being assured that the coloring matter used in the process will be thoroughly set by the process and will not readily change or fade.

In carrying out my improved process I employ a plastic or cementitious material adapted to be applied in a paste form to a surface with a brush, trowel or other similar means. The material used for the purpose of forming a substantial base for the finish to resist ordinary wear should be preferably of an inorganic and non-combustible material and further having the character of an hydraulic cement. The material I find most advantageous for use in the process is that commonly known as "gilders' whiting", chemically known as calcium carbonate.

The first step in the process consists in mixing the gilders' whiting with shellac in suitable proportions to form a paste that may be applied to a surface and adhere thereto. While I specify shellac preferably, it will be apparent as the description of my process progresses that other material may be used in place of the shellac provided it contains alcohol, vegetable matter or other organic matter that will volatilize upon the application of heat and give rise to a gas or vapor of sufficient pressure to force its way through the mass of which it forms a constituent.

Upon the mixture of gilders' whiting (calcium carbonate) and shellac being ap-

plied to requisite thickness upon a surface the coating is then subjected to a high temperature preferably by the direct impinging of a flame jet upon the coating. I have found that a blow torch is particularly advantageous to carry out this step in the process inasmuch as the heat is thus quickly applied at a high temperature and the products of combustion assist in more rapidly carbonizing the plastic base.

The heat of the flame causes the organic matter in the shellac to vaporize, particularly the alcohol, which vapors upon generating at sufficient pressure force their way outward through the mass and escape. Bubbles in the coating are formed thereby and as the vapors escape the bubbles break, leaving the requisite roughened surface of an appearance peculiar to the process and resembling antique and age worn surfaces. Coloring matter may be added to the mixture before application to the surface or the surface may be colored afterward. By virtue of the application of heat as in the former case the color pigments are well set or "burnt in" and in the latter case, the roughened surface assures of coloring readily adhering to the surface.

It is apparent that I may employ various materials having the characteristics of the

above and otherwise alter the process within the appended claims without departing from the spirit and scope of the invention.

What I claim is:

1. The process for finishing art goods including coating the surface thereof with a mixture of calcium carbonate and shellac and subjecting the coating to the flame of a blow torch. 35
2. The process for finishing art goods including coating the surface thereof with a mixture of a plastic or cementitious material and a binder containing volatile ingredients, and subjecting the coating to a flame jet. 40
3. The process for finishing art goods including coating the surface thereof with a plastic material mixed with shellac and subjecting the coating to the action of a flame jet. 45
4. The process for finishing art goods including coating the surface thereof with a mixture of calcium carbonate and a binder having volatile ingredients, and subjecting the coating to a high temperature. 50

EDWARD MUEHLBAECHER.
